UNITED STATES PATENT OFFICE.

OSCAR B. WEBER, OF NEW YORK, N. Y.

REGENERATIVE GAS-FURNACE.

SPECIFICATION forming part of Letters Patent No. 392,897, dated November 13, 1888.

Application filed June 5, 1888. Serial No. 276,130. (No model.)

To all whom it may concern:

Be it known that I, OSCAR B. WEBER, of the city, county, and State of New York, have invented certain new and useful Improvements 5 in Regenerative Gas-Furnaces, of which the following is a specification.

This invention relates to a regenerative gas-furnace of that class in which the air supplied for combustion is heated before it is mixed 10 with the products of combustion, so as to produce the more perfect combustion of the fuel; and the invention consists of a regenerative gas-furnace in which a primary series of flues for heating the air is arranged intermediately between the flues for conducting off the products 15 of combustion, the first series of air-flues supplying heated air to the fuel on the furnace-grate, while a second series of air-flues, which is also arranged between heating-flues, supplies air to the combustion-chamber of the 20 furnace, so as to produce the combustion of the fire-gases in the same. A third series of air-heating flues is arranged back of the combustion-chamber and heated by the radiation of 25 heat from the same, the air being drawn in through bottom flues below the ash-pit and supplied by an upwardly-extending rear flue having eduction-channels to the rear part of the furnace, so as to supply a third current of 30 heated air and produce the combustion of the still unconsumed fire-gases at a point above the emission-channels for the second current of air, the third or rear series of air-heating flues utilizing the space in the rear of the 35 furnace and producing the more perfect combustion of the fire-gases generated in the furnace.

In the accompanying drawings, Figure 1 represents in part a front elevation and in 40 part a vertical transverse section of my improved regenerative gas-furnace. Fig. 2 represents horizontal sections of the same on lines *x x* and *y y*, Fig. 1; and Figs. 3 and 4 represent vertical transverse sections, respectively, on 45 lines *z z* and *k k*, Fig. 1.

Similar letters of reference indicate corresponding parts.

Referring to the drawings, A represents the combustion-chamber of my regenerative gas-furnace, which combustion-chamber is arranged below the gas-retorts, which are arranged symmetrically to the vertical axis of

the furnace, as customary in a bench of gas-retorts. In the ash-pit below the grate A' is arranged a water-pan, A², which serves to receive the ashes, so as to prevent the dust from the same from passing to the outside, and also to supply a certain quantity of moisture to the heated air conducted to the fuel on the grate. 55

At each side of the combustion-chamber A, and on a level, or nearly so, with the grate A', is arranged a primary series of horizontal air-flues, B B, which communicates at the front end with an opening, b, in the front wall of the 60 furnace, so as to draw in the air, heat it in its passage through the flues B B, and conduct it through lateral eduction-channels b' into the space below the grate A', as shown in Fig. 1. This primary series of air-flues B is heated 65 up by smoke-flues C C' C², of which the flues C are arranged above and the bottom flues, C' C², below the air-flues B B, and through which the products of combustion are conducted off from the top part of the furnace to 70 the chimney C³.

A second series of air-flues, D, is also arranged at each side of the combustion-chamber A and at some distance above the grate A', the second series of air-flues receiving, like the 75 first series, atmospheric air through openings d in the front wall of the furnace, drawing the same through the flues D D, as shown in Fig. 2, and emitting it in heated state through the lateral eduction-channels d' to the upper part 80 of the combustion-chamber A, where the heated air mingles with the fire-gases generated by the incomplete combustion of the fuel on the grate and produces the combustion of the same. The air passing through the second 85 series of air-flues D is heated in the same manner as the air in the primary series by means of flues D' above and flues D² below the air-flues D, through which heating-flues D' D² the products of combustion pass from the upper part of the furnace on their way to the lower heating-flues, C C' C², and the chimney-flues C³. The retorts R are supported in the usual manner by bridge and saddle tiles, the spaces between said supporting-tiles permitting the fire-gases to pass freely around the retorts, so as to heat up the same. 95

The arrangement of a primary series of air-flues for heating the air supplied to the fuel on

the grate and the arrangement of a second series of air-flues above the first series for producing the combustion of the fire-gases at the upper part of the combustion-chamber are well known and form no part of the present invention, which consists more especially in the arrangement of a third series of air-heating flues, E, at the middle rear part of the furnace back of the combustion-chamber A, as shown in Figs. 2 and 4.

The third series of air-flues, E, receives its air-supply from openings e e in the front wall of the furnace, said openings being connected by downwardly-extending flues e' e' with longitudinal flues e² e² below the ash-pit, which latter extend through the base of the rear wall of the combustion-chamber and connect with vertical channels e³ and the third series of horizontal flues, E, where the air is heated by radiation from the rear wall and finally conducted through an upwardly-extending flue, e⁴, and eduction openings e⁵, located at the upper front part of the flue e⁴ at a point between the first and second tier of retorts, into the furnace, as shown in Figs. 1 and 4. The additional quantity of heated air supplied by the third series of air-flues mingles with the unconsumed fire-gases at the upper rear part of the furnace and burns the same, which has the effect of producing the still more complete combustion of the fire-gases and of heating up the rear ends of the retorts, where heretofore the perfect utilization of the fire-gases could not be secured, owing to the smaller depth of the combustion-chamber.

A further advantage of the third series of air-heating flues arranged at the rear part of the furnace is that the space back of the combustion-chamber is utilized and the heat at the upper rear part of the furnace increased, where heretofore the combustion was not going on as briskly as at the middle and front portions of the same.

Another and very important advantage of my improved gas-furnace is that the same has

but a small depth below the floor and that it combines compactness of construction with a high degree of economy in the consumption of fuel.

Having thus described my invention, I claim as new and desire to secure by Letters Patent—

1. In a regenerative gas-furnace, the combination of a central combustion-chamber, a primary series of air-heating flues at each side of the same, channels for supplying heated air to the grate, a second series of air-heating flues arranged above the first series, lateral channels for conducting the air heated in said flues to the upper part of the combustion-chamber, smoke-flues located above and below the primary and secondary series of air-flues, a third series of horizontal air-heating flues arranged at the rear part of the furnace, back of the combustion-chamber, air-flues connecting the bottom horizontal flue of said third series of air-flues with the front wall of the furnace, and a vertical channel connecting the top horizontal flue of said third series of air-heating flues with the upper rear part of the furnace above the eduction-channels of the second series of air-heating flues and the first tier of retorts, substantially as set forth.

2. In a regenerative gas-furnace, the combination, with the combustion-chamber, of a series of horizontal air-heating flues arranged back of the combustion-chamber at the rear part of the furnace, air-flues below the ash-pit for supplying air to said air-heating flues, and an upwardly-extending flue communicating with the air-heating flues and provided with an eduction-channel at its upper end above the first tier of retorts for discharging the heated air at the upper rear part of the furnace, substantially as set forth.

In testimony that I claim the foregoing as my invention I have signed my name in presence of two subscribing witnesses.

OSCAR B. WEBER.
